(No Model.)

G. Q. ADAMS.

ROLLER FEED FOR POWER FENCE MACHINES.

No. 445,297.

Patented Jan. 27, 1891.

UNITED STATES PATENT OFFICE.

GEORGE Q. ADAMS, OF QUINCY, ILLINOIS, ASSIGNOR TO THE ADAMS POWER FENCE MACHINE COMPANY.

ROLLER-FEED FOR POWER FENCE-MACHINES.

SPECIFICATION forming part of Letters Patent No. 445,297, dated January 27, 1891.

Application filed April 28, 1890. Serial No. 349,851. (No model.)

To all whom it may concern:

Be it known that I, GEORGE Q. ADAMS, a citizen of the United States, and a resident of Quincy, in the county of Adams and State of Illinois, have invented a certain new and useful Roller-Feed for Power Fence-Machines, of which the following is a specification.

My invention relates to improvements in machines for making picketed wire fences, and it has special relation to the apparatus which feeds the pickets in between the wires.

The general construction of the machine, including the picket-feeding devices, is or may be the same as that set forth in my United States Letters Patent, dated the 25th day of February, 1890, No. 442,172, and in order that this present invention may be more easily understood by reference to that patent I will illustrate in the drawings hereof certain of the parts shown in that patent; but I wish it to be distinctly understood that I do not limit myself to a machine constructed as the machine described and illustrated in that patent is, because my invention is applicable to any machine in which the roller-feed for the pickets is used.

The same reference-letters refer to the same parts in all the figures of the drawings hereof.

Figure 1 illustrates a plan view of so much of the said machine, partly broken away, as is necessary to illustrate this invention. Fig. 2 is an elevation, partly in section, of the parts shown in Fig. 1. Fig. 3 is an elevation of the shaft upon which the lower front feeding-roller is placed, showing the pulleys and wheels thereon.

A is a portion of the frame of the machine. It may be made in any preferred manner and of any preferred material.

B is a shaft, which is journaled in any suitable bearing C on the frame.

D is a suitable pulley whereby the shaft B may be driven. The shaft B, however, may be any shaft in the machine, or it may be a special shaft suitably driven by any moving part of the machine for this particular purpose.

E is a wheel upon the shaft B or such other

shaft as may be preferred, from which a belt F extends to a pulley G, located on a counter-shaft H. There also extends upwardly a belt I, which passes over a flanged pulley J on a counter-shaft K at the upper part of the machine. On this shaft are located the following wheels: first, a grooved pulley L; next, the flanged pulley J; next, a roller I, and next one of the lower feed-rollers M.

The shaft K is journaled, as at N, in a rocking journal, the construction of which is now well understood and does not require description. It may be of any preferred form. At its other end this shaft K works through a vertical slot K', made in a suitable bearing K'', whereby that end of the shaft may rise and fall.

N' is another lower feed-roller. It is set on a little shaft O, on the end of which is a grooved pulley P. The shaft O is journaled in any preferred manner. It has no vertical movement.

Q and Q' are the two upper feed-rollers, which have spring-cushioned journal-bearings, as shown, which are fully described in my said prior patent.

R is a wheel set upon a shaft S, which is driven in any preferred manner in proper timing with the other parts of the machine. This wheel has two dimensions, as shown, the same as in my said patent, and the wheel L on the shaft K rests upon the larger diameter of this wheel, but does not rest on the smaller diameter thereof, being prevented from dropping so far by the end of the shaft K coming in contact with the bottom of the slot K' in the bearing K'' for that end of the shaft.

T T, &c., are the twister-heads, and U is the rack-bar. These parts are or may be as set forth in my said former patent.

V are the pickets, and W the wires.

The operation is as follows: The shaft B and the pulley E being in continuous rotation, continuous movement is transmitted to the shaft H by means of the belt F, and through the belt I the shaft K is driven, but only when the belt is taut—that is to say, when the roller L is resting upon the larger diameter of wheel R; but when the end of the shaft K, upon which the feed-roller M is, drops by reason of the pas-

sage of the roller L from the larger diameter to the smaller diameter of the wheel R, then the belt I is slackened and the shaft K does not rotate, and of course the shaft O, on which the second feed-roller N'' is placed, does not rotate either. Thus the rotation of the feed-rollers M and N' is intermittent, depending upon whether the roller L on the shaft K is upon the larger diameter of the wheel R or not. It will thus be seen that the feed-rollers operate to feed the pickets into the machine at the proper time only, and that there is no possibility of the pickets being taken into the machine at an improper time. Thus accident or fracture to the machine from this cause is obviated.

It will be at once perceived by those who are familiar with this art that various modifications of the details of construction may be made and still the essential features of my invention be present.

I claim—

1. The combination, in a fence-making machine, of an upper and lower feed-roller constructed and arranged to have intermittent separation from each other, and driving mechanism for the rollers, constructed and arranged so that when the rollers are separated they will be at rest, substantially as set forth.

2. The combination, in a fence-making machine, of two sets of feed-rollers, one set constructed and arranged to have intermittent separation from the other, and driving mechanism for both sets of rollers, constructed and arranged so that they shall be at rest when the first set of rollers is separated from the other, substantially as set forth.

3. In a fence-making machine, a wheel having two diameters, a shaft supporting a feed-roller, the end of the shaft to which the feed-roller is attached being capable of limited downward movement, a roller upon the shaft, which engages with the larger diameter of the wheel having two diameters, a flanged pulley on the shaft, and a belt going over some moving part of the machinery placed below the said shaft, substantially as set forth.

Signed at New York, in the county of New York and State of New York, this 19th day of April, A. D. 1890.

GEORGE Q. ADAMS.
